AUTOMATIC ROUGE FEED FOR BUFFING MACHINES

Roger S. Sperry, Waterbury, Conn., assignor to
The Packer Machine Company, Meriden,
Conn., a corporation of Connecticut

Application May 25, 1935, Serial No. 23,453

16 Claims. (Cl. 51—263)

This invention relates to buffing machines, and more particularly to an automatic mechanism for intermittently applying abradant to a rotating buffing or polishing wheel.

One object of this invention is to provide an automatic mechanism of the above nature in which the abradant in the form of a solid block or brick is successively reciprocated and forced against the buffing wheel at regular intervals.

10 A further object is to provide a mechanism of the above nature for applying abrasive to a buffing wheel in which the block of abrasive is advanced farther on each successive stroke in order to compensate for the material removed from the block of abrasive by contact with the buffing wheel.

15 A further object is to provide a mechanism of the above nature in which the abrasive block is normally urged away from the buffing wheel by low pressure pneumatic means and is driven forwardly into contact with said wheel by automatically actuated high pressure pneumatic means which overbalances said low pressure means.

20 A further object is to provide an abradant feeding machine of the above nature in which the reciprocating abradant carriage is connected to a piston rod operating in a compressed air cylinder, the supply of air being controlled by cams mounted on the edge of a slowly rotating work carrying table.

25 A further object is to provide an abradant feed machine of the above nature in which the abradant carriage is provided with a pair of gripping plates for adjustably clamping about the sides of the abradant block, one of said plates being laterally adjustable to accommodate various sizes of blocks and both plates being simultaneously movable laterally to centralize the block with respect to the supporting table.

30 A further object is to provide an abradant feeding machine of the above nature in which the carriage is detachably connected to a threaded reciprocating plunger rod by means of a pair of jaws which may be manually released from said 35 threaded rod for permitting the carriage to be quickly returned to its initial position when the block of abrasive has been used up.

35 A further object is to provide an abradant feed mechanism of the above nature which will be comparatively simple in construction, inexpensive to manufacture, economical of abrasive and buffing wheels, easy to install and manipulate, time and labor saving, compact, and very efficient and durable in use.

With these and other objects in view, there has been illustrated on the accompanying drawings, one form in which the invention may be conveniently embodied in practice.

In the drawings:

Fig. 1 represents a perspective view of the abradant feeding mechanism as it appears when installed upon a conventional buffing machine.

Fig. 2 is a vertical sectional view taken through the pneumatic control valve and the edge of the 10 rotating work carrying table.

Fig. 3 is a top plan view of the pneumatic control valve.

Fig. 4 is a horizontal sectional view of the same taken along the line 4—4 of Fig. 2, looking in the 15 direction of the arrows.

Fig. 5 is a top plan view of the abradant feeding mechanism, per se.

Fig. 6 is a front elevation of the same, partly in section, and with portions broken away to 20 show the interior construction.

Fig. 7 is a transverse vertical section taken along the line 7—7 of Fig. 5.

Fig. 8 is a similar transverse sectional view taken along the line 8—8 of Fig. 5.

Fig. 9 is a horizontal sectional view of the abradant feed carriage taken along the line 9—9 of Fig. 6, looking downwardly.

Fig. 10 is an exploded perspective view of the ratchet feeding mechanism for advancing the 30 block carriage farther on each successive stroke to compensate for the amount of abrasive worn from the block.

Fig. 11 is a similar exploded view of the split clamping jaws for connecting the block carriage 35 to the threaded section of the plunger shaft, and showing the means for enabling the carriage to be quickly released therefrom.

Fig. 12 is a detail perspective view of the guide bracket for slidably supporting the clamping 40 jaws.

Referring now to the drawings in which like reference numerals denote corresponding parts throughout the several views, the numeral 10 indicates the top of a stationary table above which 45 is a slowly rotating work carrying platform 11. Journalled upon the platform 11 are a plurality of rapidly revolving vertical spindles 12 having work holding heads 13 for supporting articles 14 to be buffed. The revolving spindles 12 are 50 adapted to be slowly carried by the rotation of the platform 11 into the path of one or more buffing wheels 15 (only one being shown in the drawings).

Located at right-angles to the axis of the buff- 55

ing wheel 15 is an elevated elongated flat rouge carriage supporting table 16 having an integral depending side angle bracket 17 which is connected by a tongue and groove with the upper 5 platform 18 of an angular inclined bracket 19. The base of the bracket 19 is supported and rigidly secured upon a relatively heavy horizontal plate 20 which is adapted to be mounted upon any suitable fixed standard. The base 17a of 10 the depending angle bracket 17 is provided with a pair of elongated slots 21 through which pass a pair of bolts 22 having threaded engagement in the platform 18,—this construction being such that the rouge carriage supporting table 16 may 15 be moved longitudinally with respect to the platform 18 and clamped in any desired adjusted position by means of said bolt 22.

Reciprocating rouge holding carriage

20 A cake 23 of abradant buffing material in the shape of a rectangular brick or block shown in dot and dash lines in Figs. 1, 5 and 6 is adapted to rest upon the table 16, and is adapted to slide along the top thereof into and out of engagement with the periphery of the adjacent buffering wheel 15. The rear end of the rouge block 23 abuts against a rouge carriage 24 having a pair of laterally clamping plates 25 and 26 slidably fitted therein, said plates being adapted to tightly grip the opposite sides of the rear end of the rouge block 23.

The rouge carriage 24 extends transversely across the top of the supporting table 16, and is provided with an integral rearwardly extending horizontal flat section 24a having a depending elongated tongue 27 having slidable engagement in a longitudinal guiding slot 28 extending centrally along the table 16.

Located directly underneath the carriage 24 40 of the table 16 is a sliding jaw guide block or bracket 29 having a rearwardly extending section 30 provided with an upwardly formed tongue 31 adapted to fit the slot 28 and engage the depending tongue 27 of the section 24a. The carriage 24 and guide bracket 29 are adapted to be held together on opposite sides of the table 16 by means of a pair of cap screws 32 passing through suitable apertures in the section 24a and screwed into corresponding tapped holes 33 50 provided in the section 30 of the guide bracket 29 (see Fig. 12).

The assembled carriage 24 and guide bracket 29 are adapted to be reciprocated along the table 16 by means of a plunger rod 34 located under said table. The forward end of the plunger rod 34 is slidably supported in a hanger bearing 35 made rigid to the underside of the table 16, and the rear end of said plunger rod is supported in a cylinder 36 to be described later. The plunger rod 34 is provided with an intermediate threaded section 37 which is adapted to be connected to the reciprocating carriage 24 by means of a pair of cooperating jaws 38 and 39 having semi-cylindrical threaded sections 40 and 41 for engaging upon opposite sides of the threaded section 37 of the piston rod 34. The jaws 38 and 39 are adapted to slide transversely in the guide bracket 29 in a pair of opposed parallel guideways 42 provided therein.

In order to uncouple the jaws 38 and 39 from the threaded section 37 of the plunger rod 34 so that the carriage 24 may be moved independently of said rod 34, said jaws are provided with a pair of upstanding guide pins 43 and 44 which are adapted to engage in a pair of arcuate cam grooves 45 and 46 formed in a disc member 47.

As clearly shown in Figs. 8 and 12, the disc member 47 is mounted to oscillate in a circular aperture 48 provided in the sliding jaw bracket 29, and is provided with an upwardly extending shaft 49 journaled in a suitable vertical hole 49a provided in the carriage 24. The shaft 49 extends above the carriage 24 and is provided at its upper end with a hand wheel 50.

It is to be noted from Fig. 11 that the arcuate slots 45 and 46 are eccentrically positioned with respect to the axis of the disc member 47 so that when the hand wheel 50 is turned, the jaws 38 and 39 will be spread apart for disengaging them from the threaded sections 37 of the plunger rod. This will allow the carriage 24 to be moved independently of the plunger rod 34.

Compressed air cylinder

In order to cause the plunger rod 34 to be reciprocated for alternately forcing the rouge block against the buffering wheel and then retracting said block therefrom, compressed air will be admitted to opposite sides of the cylinder 36 previously mentioned. The cylinder 36 comprises a cylindrical housing 51 having integral flat oppositely extending flanges 51a on its upper side by means of which said housing 51 may be attached to the underside of the rouge carriage supporting table 16 adjacent the rear end thereof by means of cap screws 52. The opposite ends of the cylindrical housing 51 are adapted to be closed by means of a pair of front and rear end caps 53 and 54, thus providing a tightly sealed piston chamber 55 within the housing 51.

The front end cap 53 is provided with an axial bore 56 surrounding the plunger shaft 34 and rendered leak-proof by means of a threaded gland member 57 and a packing ring 58. The rear extremity of the shaft 34 is provided with a reduced section 59 for receiving a piston head 60 comprising a pair of opposed cupped leather washers 61, 61 held between a central metal spacing washer 62 and a pair of end collars 63, 63. The washers 61, 61 and the collars 63, 63 are adapted to be tightly clamped against a shoulder 64 formed at the junction of the reduced section 59 and the shaft 34 by means of a pair of locking nuts 65.

In order to admit low pressure and high pressure air to the opposite sides of the piston head 60 respectively, the end caps 53 and 54 are provided with ports 66 and 67 opening into the chamber 55. The ports 66 and 67 have nipples 68 and 69 threadedly screwed therein, said nipples being connected respectively to a low pressure hose line 70 and a high pressure hose line 71, the latter pipe 71 being connected to a pneumatic control valve 72 located on the buffering machine.

Pneumatic control valve

The pneumatic control valve 72 comprises a circular shaped cover member 73 having a rearwardly extending angular bracket 74 attached to a spacing block 75, which in turn is secured rigidly to the depending side wall of the buffering table 10 (see Figs. 1 and 2). A hollow flanged body member 76 having a stepped lower section is secured to the underside of the cover member 73 by means of cap screws 77, a valve chamber 78 being enclosed therebetween.

The cover member 73 is provided with three radial semi-cylindrical raised bosses 79, 80 and 81 on its top surface. The outer ends of the bosses 79 and 80 are provided with tapped holes 79a and 80a, respectively, which communicates with a pair of reduced angular orifices 79b and 80b.

88b leading into the valve chamber 78. A nipple 82 is screwed into the tapped hole 79a and is adapted to receive one end of the high pressure line 71. The other tapped hole 88a of the boss 5 88 is fitted with an elbow nipple 83 which is directed downwardly and is open to the atmosphere to serve as an exhaust port for the control valve 72.

The bottom of the stepped body member 76 is 10 provided with a tapped port 84 for receiving a nipple 85, which is connected to a hose feed line 86 leading to any convenient supply of compressed air or other suitable operating fluid under high pressure. Ordinarily the high pressure line 86 15 will be supplied with air at about 80 pounds per square inch, while the pressure in the low pressure line 78 will preferably be maintained at about 25 pounds per square inch.

The center of the cover member 73 is provided 20 with a hollow upstanding boss 87 in which is journaled a valve-operating shaft 88 having attached to its lower end a valve sector 89, as by means of a transverse pin 90 (see Figs. 2 and 4). The top surface of the valve sector 89 is provided 25 with a pair of depressed arcuate grooves 91 and 92, the former groove being longer than the latter. The groove 91 normally connects the orifice 79b leading to the pipe 71, with the orifice 88b leading to the exhaust nipple 83. The short 30 groove 92 is provided with a vertical passage 93 leading to the chamber 78.

In order to cause the control valve 72 to apply rouge to the buffing wheel 15 during the interval between the buffing operations thereof, the operating shaft 88 is provided at its upper end with a lateral arm 94 having a bifurcated free end 95 for embracing a roller 96 held in place by means of a vertical pivot pin 97. The pivot pin 97 is provided with a depending enlarged extension 98 40 which is normally held by a coiled spring 99 against a raised fin 100, forming an integral part of the cover member 73. The depending extension 98 is provided with a circumferential groove 101 for receiving one end of the helical spring 99 45 while the opposite end of said spring is attached to the inturned horizontal end 102 of an L-shaped rod 103 fitting in a hole 104 provided in the raised boss 81 of the cover 73.

A plurality of cam trip blocks 105 (one only 50 being shown on the drawings) are secured on the periphery of the rotating work platform 11. Each trip block 105 is provided with an outwardly extending pyramid-shaped nose 106 which engages the roller 96 by a cam action, and is adapted to 55 oscillate the valve sector 89 in a counter-clockwise direction. This will bring the short arcuate slot 92 into registry with the orifice 79b, allowing air under high pressure to rush into the hose line 71 and be admitted to the right-hand 60 or outer end of the piston cylinder 36, as viewed in Figs. 1 and 6. The piston head will thus be forced to the left causing the rouge block 23 to be forcibly applied to the edge of the revolving buffing wheel. When the roller 96 passes beyond 65 the trip block 105, the spring 99 will immediately return the sector 89 to its original position, allowing the high pressure air to escape from the outer end of the cylinder and permitting the abrasive block to be retracted from the buffing wheel 70 by the low pressure air which is exerted constant- ly on the left-hand side of the piston.

Compensating mechanism

In order to compensate for the amount of abrasive removed from the rouge block 23 each time 75

it engages the buffing wheel 15, provision is made of an L-shaped bracket 107 secured adjacent the front edge of the table 16 and depending downwardly therefrom. The rear wall of the bracket 107 carries an adjustable loop-shaped box cam 5 108 having an integral laterally extending trunnion 109 reduced and threaded at its extremity 110. The trunnion 109 is journaled in a horizontal aperture 111 provided in the vertical wall of the L-shaped bracket 107. The box cam 108 10 is held flat against the bracket 107 by means of a nut 112 and a washer 113 mounted on the threaded end of the trunnion 109 outside the bracket 107.

The rear end of the box cam 108 is provided 15 with an integral tapped lug 114 for receiving a binding screw 115 which projects through and is slidable in an arcuate slot 116 provided in the depending wall of the bracket 107. This construction permits the box cam 108 to be manually 20 tilted to any desired adjusted angular position, after which the cam may be locked by manipulating a head 115a on the end of said screw 115.

In order to visually indicate the exact angular position of the box cam 108, provision is made of 25 a small angular scale plate 117 attached to the left side edge of the bracket member 107, as viewed in Fig. 6. The plate 117 is provided with a graduated scale 118, which is adapted to be read 30 with reference to a fixed indicating line 119 located on the adjacent exposed end of the box cam 108.

Directly in back of the bracket 107 and rigidly mounted upon the plunger rod 34 is a ratchet wheel 120 (see Figs. 7, 8 and 10), and mounted on 35 the rod 34 adjacent the ratchet wheel 20 is a bell-crank lever 121. The rearwardly extending arm 121a of said lever is provided with a pivoted pawl 122 which is adapted to engage with the teeth of the ratchet wheel 120. The pawl 122 is urged 40 against the ratchet wheel 120 at all times by means of a small helical tension spring 123 connected at its ends to a pair of pins 124 and 125 mounted on the pawl 122 and the lever 121, respectively. The opposite end of the arm 121b of 45 the bell-crank lever 121 carries a transverse follower wheel 126 which is adapted to ride within the box cam 108.

In order to hold the ratchet wheel 120 against reverse rotation, provision is made of a relatively 50 broad horizontal flat leaf-spring 127 attached to the lower edge of the bracket 107 by means of screws 128 and projecting inwardly therefrom. The inner free end of the spring 127 is provided 55 with an upturned bent extremity 129 which is adapted to engage with the ratchet wheel 120.

Rouge clamping jaws

The adjustable rouge clamping jaws 25 and 26 are provided with integral tongued guide blocks 60 131 and 132, which are adapted to slide in a T-shaped guide slot 133 extending across the entire front face of the carriage member 24. The guide block 131 of the rear clamping plate 25 is provided with a horizontal hole 134 in which is rotatably journaled a reduced section 135 of a horizontal adjusting screw 136. The rear end of the reduced section 135 has a rigid collar member 137 to prevent axial movement of the adjusting screw 136 with respect to the clamping plate 25. The 65 forward end of the adjusting screw 136 is provided with a rigid winged turning handle 138. A hollow section 139 is provided adjacent the T-shaped slot 133, and said section is open at the rear of the carriage 124 to receive a rearwardly 70 75

projecting lug 140 forming an integral part of the tongued block 131. The lug 140 is provided with a tapped hole 140a for receiving a clamp centralizing screw 141, extending forwardly to the front of the carriage and being provided with a kerfed head 142. An integral thrust collar 143 is provided between the head 142 and the threaded section of the screw 141, said collar 143 being seated in the base of a countersunk socket 144 and held against axial movement by means of an outer bushing 145 tightly fitting in said countersunk socket 144.

It will be noted from the above construction that by merely turning the winged handle 138, the rouge block clamping plate 26 may be adjusted inwardly or outwardly in a transverse direction to accommodate various sizes of abrasive blocks. It will also be noted that by turning the kerfed screw 141 with the aid of a screw driver, the screw 136 together with the clamping plates 25 and 26 will be moved as a unit to any desired adjusted position with respect to the buffering wheel.

As best shown in Fig. 1, the adjacent faces of the rouge block engaging plates 25 and 26 may be provided with knurled or roughened gripping areas.

In order to protect the working mechanism of the abradant feed machine from the dust created by the buffering machine, provision is made of an angular shaped dust guard 146 located at the rear of the supporting table 116. The dust guard 146 is held in position under the table 16 by angle brackets 147.

Dust is also excluded from the rear of the slot 28 in the rouge carriage by a guard strip 148 attached to the rear part 24a of the rouge carriage 24 by means of the cap screws 32. The guard strip 148 is offset downwardly so that the rear end thereof will lie flat upon the top of the table 16.

It will be understood that the rouge block 32 normally covers the forward end of the slot 28, and hence excludes dust therefrom.

45

Operation

In the operation of the rouge feeding mechanism, whenever one of the cam trip blocks 105 carried by the rotating table 11 engages the roller 96 carried by the lateral arm 94 of the control valve 72, the valve sector 89 will be swung in a counter-clockwise direction as viewed in Figs. 3 and 4. This will connect the pipe line 86 to the hose line 71, and admit compressed air under high pressure at the right of the piston head 60, causing the plunger rod 34 to move forwardly in the cylinder 36 as far as it will go. The forward thrust of the plunger rod 34 will carry the carriage 24 along the table 16 and will cause the rouge block 23 to strike the face of the buffering wheel 15 and apply the desired amount of rouge thereto.

As soon as the trip block 105 has passed the roller 96, the lateral arm 94 will be moved back to its normal position by the helical spring 99, and in this position the valve sector 89 will again connect the orifice 79b with the orifice 80b through the elongated arcuate groove 91. This will permit the "high pressure" compressed air in the rear of the cylinder 36 to escape to the atmosphere through the exhaust nipple 83. The plunger 60 will then be forced rearwardly to its normal inactive position by the continuous pressure on the piston head of the compressed air from the low pressure pipe line 10 which is in communication with the left-hand or forward end

of the cylinder chamber 55 at all times. It will be understood that the high pressure exerted at the rear of the cylinder when the rouge plunger is operated, will be sufficient to overbalance the constant low pressure on the forward end thereof. 5

To compensate for the wearing off of the rouge block by its contact with the buffering wheel on each forward thrust of the plunger rod 34, the follower wheel 126 on the end of the ratchet operating bell-crank lever 121 will be caused to ride 10 forwardly in the cam slot of the box cam 108, and consequently will be forced downwardly due to the inclination of said box cam. This action will cause the bell-crank lever 121 to tilt about the axis of the shaft 34 and twist said shaft in a counter-clockwise direction with it by means of the ratchet wheel 120 and pawl connection 122. The split jaws attached to the rouge block carriage 24 will thus be moved forwardly the required distance. 20

It will be understood that a greater or lesser degree of compensating movement on the part of the carriage 24 may be readily accomplished by merely adjusting the box cam 108 to different angular positions within the limits of the arcuate 25 slot 116. This is performed by manipulating the binding screw 115 to the desired extent.

While there has been disclosed in this specification one form in which the invention may be embodied, it is to be understood that this form is 30 shown for the purpose of illustration only, and that the invention is not to be limited to the specific disclosure but may be modified and embodied in various other forms without departing from its spirit. In short, the invention includes all the 35 modifications and embodiments coming within the scope of the following claims.

Having thus fully described the invention, what is claimed as new, and for which it is desired to secure Letters Patent is:

1. In a mechanism for automatically feeding abrasive to a buffering wheel, a holder for a cake of abradant material, a plunger rod connected to said holder, a cylinder, said plunger rod carrying a piston operable in said cylinder, means for constantly supplying air at low pressure to said cylinder on the side of said piston adjacent said holder to normally keep said abradant cake away from said buffering wheel, means for supplying air at a high pressure for a short period of time to 50 said cylinder on the other side of said piston to overbalance the low pressure and cause said cake to move forward and strike said buffering wheel. 45

2. In a mechanism for automatically feeding abrasive to a buffering wheel, a holder for a cake 55 of abradant material, a plunger rod connected to said holder, a cylinder, said plunger rod carrying a piston operable in said cylinder, means for supplying air at low pressure to said cylinder on one side of said piston to normally keep said abradant 60 cake away from said buffering wheel, means for periodically supplying air at a higher pressure to said cylinder on the other side of said piston to overbalance the low pressure and cause said cake to move forward and strike said buffering wheel. 65

3. In a mechanism for automatically feeding abrasive to a buffering wheel, a holder for a cake of abradant material, a plunger rod detachably connected to said holder, a compressed air cylinder, a piston operable in said cylinder and connected 70 to one end of said rod, means for supplying air at low pressure to one end of said cylinder for pressing upon said piston to normally keep said abradant cake away from said buffering wheel, means for supplying air at a higher pressure to 75

the opposite side of said cylinder to move said plunger rod forwardly and cause said abradant to strike said buffing wheel, and valve means for periodically connecting said high pressure air supply to said cylinder.

4. In a mechanism for automatically feeding abrasive to a buffing wheel, a movable work carrying table, a holder for abradant material, a plunger rod connected to said holder, pneumatic means for normally holding said plunger rod away from said buffing wheel, pneumatic means for forcing said plunger toward said buffing wheel to cause said material to be applied to said wheel, a valve for controlling the operation of said second mentioned pneumatic means, said valve being operated by the movement of said table.

5. In a mechanism for automatically feeding abrasive to a buffing wheel, a movable work carrying table, a holder for abradant material, a plunger rod connected to said holder, pneumatic means for normally urging said plunger rod away from said buffing wheel, pneumatic means for intermittently forcing said plunger toward said buffing wheel to cause said abradant to be applied to said wheel, a valve for controlling the operation of said second mentioned pneumatic means, said valve being operated by the movement of said table, and means on said valve to render inoperative said second mentioned pneumatic means at the end of the forward stroke of said plunger rod.

6. In a mechanism for automatically feeding abrasive to a buffing wheel, a movable work carrying table, a holder for abradant material, a plunger rod connected to said holder, means for normally urging said plunger rod away from said buffing wheel, pneumatic means for forcing said plunger toward said buffing wheel to cause said abradant to be applied to said wheel, a valve for controlling the operation of said pneumatic means, said valve being operated by the movement of said table, and means on said valve to render inoperative said pneumatic means at the end of the forward stroke of said plunger rod.

7. In a mechanism for automatically feeding abrasive to a buffing wheel, a stationary platform, a carriage member slidably on said platform for holding abradant material, a slidable plunger rod mounted underneath said platform and connected to said carriage, means for normally urging said plunger rod away from said buffing wheel, and periodically operated pneumatic means for overbalancing said first mentioned means and moving said rod in the opposite direction to cause said cake to be forcibly applied to said buffing wheel.

8. In a mechanism for automatically feeding abrasive to a buffing wheel, a stationary platform mounted adjacent said buffing wheel, an abrasive holding carriage slidably mounted on said platform and movable toward and away from said buffing wheel, a slidable plunger rod mounted underneath said platform and connected to said carriage, pneumatic means for moving said plunger rod to apply abrasive to said buffing wheel, and pneumatic means for thereafter moving said rod in the opposite direction away from said buffing wheel.

9. In a mechanism for automatically feeding abrasive to a buffing wheel, a platform, a holder for abrasive slidably mounted on said platform, a slidable plunger screw mounted underneath said platform, means for threadedly connecting said screw to said holder, pneumatic means for periodically reciprocating said screw to carry said abrasive into and out of contact with said buffing

wheel, and means for slightly twisting said screw at each stroke thereof to cause said holder to be moved forwardly an increasingly greater amount to compensate for the material applied to said buffing wheel.

10. In a mechanism for automatically feeding abrasive to a buffing wheel, a platform, a holder for abrasive slidably mounted on said platform, a slidable plunger screw mounted underneath said platform, means for detachably and threadedly connecting said screw to said holder, means for periodically reciprocating said screw to carry said abrasive into and out of contact with said buffing wheel, and means for slightly twisting said screw at each stroke thereof to cause said holder to be moved forwardly an increasingly greater amount to compensate for the material applied to said buffing wheel.

11. In a mechanism for automatically feeding an abrasive material to a rotating buffing wheel, a reciprocating holder for said abrasive material, a plunger rod threadedly connected to said holder for periodically applying said material to said buffing wheel, a ratchet wheel fixed to said plunger rod, a bell-crank lever journaled on said rod, a pawl pivoted to one end of said bell-crank lever for engaging the teeth of said ratchet, cam-operated means for rocking said lever on each forward stroke of said rod, whereby said holder will be moved progressively farther on each successive stroke to compensate for the abrasive applied to said buffing wheel, and means to prevent rearward rotation of said ratchet wheel.

12. In a mechanism for automatically feeding abrasive material to a rotating buffing wheel, a reciprocating holder for said material, a plunger rod threadedly connected to said holder for periodically moving said material into and out of contact with said buffing wheel, a ratchet wheel fixed to said plunger rod, a bell-crank lever journaled on said rod, a pawl pivoted to one end of said bell-crank lever for engaging the teeth of said ratchet, cam-operated means for rocking said lever on each forward stroke of the holder, whereby said holder will be moved closer and closer to said buffing wheel on successive strokes to compensate for the abrasive applied to said buffing wheel, means to prevent rearward rotation of said ratchet wheel, and means for adjusting said cam-operated means to vary the amount said rod will be rocked on each stroke.

13. In a mechanism for automatically feeding abrasive material to a rotating buffing wheel, a reciprocating holder for said material, a plunger rod threadedly connected to said holder for periodically moving said material into and out of contact with said buffing wheel, a ratchet wheel fixed to said plunger rod, a bell-crank lever journaled on said rod, a pawl pivoted to one end of said bell-crank lever for engaging the teeth of said ratchet, a pivotally mounted slotted box cam embracing the other end of said lever, said cam being fixed in position, means to vary the inclination of said cam to control the rocking of said lever on each successive stroke of the holder to determine accurately the amount of abrasive applied to said buffing wheel.

14. In a mechanism for automatically feeding an abrasive material to a rotating buffing wheel, a reciprocating holder for said material, a plunger rod threadedly connected to said holder for periodically moving said material into and out of contact with said buffing wheel, a ratchet wheel fixed to said plunger rod, a bell-crank lever journaled on said rod, a pawl pivoted to

- one end of said bell-crank lever for engaging the teeth of said ratchet, a pivotally mounted slotted box cam embracing the other end of said lever, said cam being fixed in position, means to vary the inclination of said cam to control the rocking of said lever on each stroke of the holder to determine accurately the amount of abrasive applied to said buffing wheel, and scale means to indicate the exact setting of said cam.
- 10 15. In a mechanism for automatically feeding abrasive to a buffing wheel, a holder for abrasive material, a plunger rod connected to said holder, means to normally urge said rod to retracted position, fluid operated means to overbalance said retracting means and force said rod forwardly to apply said abrasive to said buffing wheel, a source of fluid pressure, and a periodi-

cally opened valve to connect said source to said fluid operated means.

16. In a mechanism for automatically feeding abrasive to a buffing wheel, a holder for abrasive material, a plunger rod connected to said holder, 5 means to normally urge said rod to retracted position, fluid operated means to overbalance said retracting means and force said rod forwardly to apply said abrasive to said buffing wheel, a source of fluid pressure, and a periodically 10 opened valve to connect said source to said fluid operated means, said valve also having means to exhaust said fluid at the end of the stroke of said abrasive holder to permit said retracting means to again become effective. 15
